INVENTOR
Charles C Hansen
BY *Herbert G. Odgen*
HIS ATTORNEY.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

FEED-SCREW MOTOR FOR ROCK DRILLS.

Application filed January 19, 1926. Serial No. 82,272.

This invention relates to rock drills, but more particularly to a device for producing relative movement between a rock drill and its supporting shell.

5 The objects of the invention are to enable a rock drill to be quickly withdrawn from the work, to increase the efficiency of the drifter and other similar types of rock drills supported and guided by shells, and to 10 eliminate the slow and arduous method of rotating the feed screw by hand.

The invention consists of the combination 15 of elements and arrangement of parts substantially as hereinafter described and more particularly pointed out in the appended claims and illustrated in the accompanying drawings, in which—

Figure 1 is an elevation, partly in section, of a rock drill and its shell equipped with 20 a motor connected to rotate the feed screw,

Figure 2 is a perspective view, partly in section, of the motor casing,

Figure 3 is a transverse section taken 25 through Figure 1 on the line 3—3 looking in the direction of the arrows, and

Figure 4 is a view similar to Figure 1 showing the motor mounted coaxially with the feed screw.

Referring to the drawings, and at first 30 more particularly to Figure 1, the invention is shown applied to a rock drill A supported and guided by a shell B in the usual manner. The rock drill A accordingly has guides C formed on opposite sides thereof 35 to cooperate slidably with suitable guideways (not shown) formed in the shell B.

In order to produce relative longitudinal movement between the rock drill illustrated and its shell, it is the usual practice to employ a feed screw of any suitable type. The feed screw thus employed is usually anchored at one end in the shell in such a manner that it is permitted to rotate freely but is held against longitudinal movement. 45 Accordingly in this instance a feed screw D extends through the shell B in the manner described and engages a feed nut E carried by the rock drill A.

By means of this construction, the rock 50 drill may be advanced to the work or withdrawn therefrom, depending upon the direction in which the feed screw D is being rotated.

In accordance with the present invention,

the rearward end F of the feed screw D is 55 supported by a bearing bracket G and extends rearwardly thereof. The end F thus extending beyond the bearing bracket G is preferably of square cross section to receive a bevel gear H which may be held against 60 endwise movement with respect to the feed nut D in any suitable manner, as by a pin J extending transversely through the gear H and the end F of the feed screw D.

In order to support the bearing bracket 65 G at a distance sufficiently to the rearward end of the shell B to prevent interference between said bearing bracket and the rock drill A as the rock drill is moved to its rearward limiting position, a pair of rods K, only 70 one of which is shown in side view in the figures, are supported by the rearward end of the shell B and on opposite sides thereof to support at their free ends the bearing bracket G. The rods K may be in the form 75 of tie-rods and are threaded at their ends to receive nuts L.

Usually in rock drills of the type illustrated, a crank or other suitable means is secured to the feed screw whereby the operator may rotate said feed screw, both for feeding the drill into the rock and also for withdrawing the drill from the work after the drilling operation is completed. During 80 the drilling operation the forward movement 85 of the drill is of necessity slow since such movement is dependent upon the penetration of the drill steel into the work. After the cut is completed, however, it is desirable to withdraw the drill in the shortest time possible 90

so that the drill steel may be changed with the minimum loss of time. In the method of manipulating the feed screw heretofore employed, such withdrawal of the 95 drill requires considerable time and, in consequence, reduces the drilling efficiency considerably. To the end that such changes of the steel may be made quickly and the drilling may be expedited, a motor designated generally by O is mounted at the rearward end of the shell B. A casing P of the motor O in this instance has a pair of lugs Q which extend at an angle to said casing and are provided with apertures R through 100 which the rods K may extend for supporting the motor. The motor O is preferably clamped in position by a pair of spacers S on the rods K and interposed between the

2
lugs Q of the motor and the bearing bracket G, thus serving both as a means for clamping the motor in position and as an abutment for the bearing bracket.

5 The motor O in this instance comprises a chamber T formed on one side of the casing P and in which chamber are arranged the gears U and V which comprise the power element of the motor. The gear V in this 10 instance carries a worm W rotatable in a gear casing X forming a part of the casing P and the rearward portion thereof. The worm W is preferably formed integrally with the shaft Y whereby said worm is connected to the gear V and meshes with a worm wheel Z arranged freely rotatable on the shaft b. One end of the shaft b may be supported in the casing P in any suitable manner and is supported at its other end by the 15 bearing bracket G. The rearward end of the shaft b, like the corresponding end of the feed screw D, is also preferably provided with a square portion F to receive a bevel gear c which meshes with the gear H carried by the feed screw D. Disposed near the front end of the shaft b is a clutch of any suitable type, shown in this instance as a jaw clutch having a clutch collar d slidable on the forward squared end of the shaft b and 20 thus held against rotation with respect thereto. A clutch yoke e pivoted at one end as at f engages the clutch collar d in the usual manner and is provided with a handle g whereby the clutch collar having jaws may 25 be actuated into engagement with a clutch member h having cooperating jaws and carried by the worm wheel Z.

In order that the clutch collar d may be automatically disconnected from the clutch 30 member h when manual pressure on the handle g is released, a retracting spring j is secured at one end to the clutch yoke e between the pivot f and the clutch collar d and is anchored at its other end to a projection k 35 preferably formed integrally with a cover o secured to the end of the gear casing X.

To the end that the feed screw D may be manually rotated for advancing the rock drill to the work, a crank p is secured to the 40 front end of the shaft b to abut the end of the cover o and thus prevent rearward movement of the shaft b.

The motor O is in this instance illustrated as a one direction motor and pressure fluid 45 supplied to a throttle valve q through a supply line r may be admitted through a passage t leading from the throttle valve to the motor. Suitable exhaust ports u are conveniently formed in the motor casing for exhausting the pressure fluid to the atmosphere.

The operation of the device is as follows: With the drill in the position shown in Figure 1, or in other words, its rearward limiting 55 position with respect to the shell B, the

drill A may be set in operation and as the drill steel penetrates the rock, the operator may, by rotating the crank p, impart rotary movement to the feed screw D and thus advance the drill in accordance with the penetration of the drill steel into the rock. After the drill steel has penetrated the rock to the limit of its length, and it is desired to withdraw the same from the work, the clutch collar d may be actuated by the handle g 75 into engagement with the clutch member h carried by the worm wheel Z. Pressure fluid may then be admitted to set the motor in operation. With the clutch members in engagement, rotation of the motor will be 80 transmitted through the shaft b to rotate the feed screw rapidly in the direction required for imparting retrograde movement to the drill with respect to the shell.

In the modification shown in Figure 4, a 85 motor O, similar in all essential respects to the motor described in connection with the preferred modification, is shown mounted on the rearward ends of the rods K. The motor casing P in this instance is provided 90 with lugs v at its forward end to abut the rearward ends of the spacers S and to receive the rearward ends of the rods K. In this instance the motor O is so arranged that the worm gear Z is coaxial with the feed 95 screw D' and is arranged rotatably on an extension w formed on the rearward end of the feed screw D'. The clutch collar d in this instance is arranged on the squared rearward end of the extension w as is also 100 the crank p. It will be seen that in this modification, the motor O is connected directly to the feed screw D, thus forming a combination which is particularly advantageous for use in "short hole" drilling. 105

I claim:

1. The combination of a rock drill, a shell therefore, a feed screw rotatable in the shell and operatively connected to the rock drill, rods supported by the shell and extending rearwardly thereof, a bearing bracket on the free end of the rods to support one end of the feed screw, a rotary motor, a motor bracket supported by the rods, a shaft adapted to be rotated by the motor and supported at one end by the bearing bracket, and gears on corresponding ends of the feed screw and the shaft meshing with each other to transmit the rotary movement of the motor to the feed screw for imparting retrograde movement to the rock drill with respect to the shell. 110

2. The combination with a rock drill, a shell therefore, a feed screw rotatable in the shell and operatively connected to the rock drill, of a gear carried by one end of the feed screw, a rotary motor secured to the shell, said motor comprising a pair of fluid actuated gears, a worm carried by one of the gears, a worm wheel meshing with the worm 120 125 130

and carrying a clutch member, a shaft extending rotatably through the worm wheel and forming a bearing therefore, a gear on one end of the shaft meshing with the gear 5 on the feed screw for transmitting rotary movement of the motor to the feed screw, a clutch collar slidable on the shaft to cooperate with the clutch member for preventing

relative movement between the worm wheel and the shaft, a spring for automatically 10 releasing the clutch collar from the clutch member, and a crank on the shaft for manually rotating the feed screw.

In testimony whereof I have signed this specification.

CHARLES C. HANSEN.
